UNITED STATES PATENT OFFICE.

HARVEY L. HOPKINS, OF CHICAGO, ILLINOIS, ASSIGNOR OF ONE-HALF TO JOHN HOWARD McELROY, INDIVIDUALLY, AND ONE-HALF TO JOHN HOWARD McELROY, TRUSTEE, OF CHICAGO, ILLINOIS.

CUTTING APPARATUS.

1,190,411.

Specification of Letters Patent.

Patented July 11, 1916.

Application filed November 1, 1913. Serial No. 798,637.

To all whom it may concern:

Be it known that I, HARVEY L. HOPKINS, a citizen of the United States, and a resident of Chicago, in the county of Cook and State 5 of Illinois, have invented certain new and useful Improvements in Cutting Apparatus, of which the following is a full, clear, and exact specification.

My invention is concerned with an improvement in the cutting apparatus shown 10 in my Patent No. 1,158,500, dated November 2, 1915, in which the lugs, which were permanently fixed on the knife sections, had to be set farther back than they should have 15 been to secure the most efficient action in holding the sections down on the ledger-plates in order to prevent their interfering with the grinding of the knife-sections, and even with the lugs set back to the proper 20 position, it was somewhat inconvenient to grind the adjacent sections. To remedy this difficulty, in my present invention I make said lugs removable from the knife-sections in such a manner that they are securely held 25 in operative position while the bar is in the machine, and yet are free to be removed entirely or swung out of the way when the knife-sections are inverted, as they are for 30 grinding. By my present improvement, I not only remedy this objection arising from the difficulty of grinding the adjacent knife-sections, but I am enabled to place the lugs 35 farther forward on the sections, so that their action in holding the knife-sections down on the ledger-plates is as perfect as could be desired.

To illustrate my invention, I annex hereto two sheets of drawings, in which the same reference characters are used to designate 40 identical parts in all the figures, of which,—

Figure 1 is a top plan view of a portion of a cutter-bar embodying my invention; Fig. 2 is a section on the line A—A of Fig. 1; Fig. 3 is a section through the sickle when 45 it is removed from the machine, and as it appears when held in position for grinding the sections; Fig. 4 is a perspective view of the lug-supporting member which I preferably employ; Fig. 5 is a similar view of the 50 lug detached therefrom; Fig. 6 is a view similar to Fig. 1, but with the clip omitted, showing a modified construction; Fig. 7 is a view in section on the line B—B of Fig. 6; Fig. 8 is a perspective view of the lug em-

ployed in this form of my invention; Fig. 9 55 is a view similar to Fig. 7, but showing a still further modification; Fig. 10 is a top plan view showing the knife-section employed in the modification shown in Fig. 9; Fig. 11 is a perspective view of the lug used 60 in the modification shown in Figs. 9 and 10; and Fig. 12 is a perspective view of a lug which may be employed in a still further modification.

In carrying out my invention, the finger 65 bar *f* and guard fingers *g*, secured thereto by bolts *h*, are of the customary construction; and the cutter-bar *e* and knife-sections *j*, secured thereon by rivets *k*, are of the customary construction in the form shown in 70 Figs. 1 to 8, inclusive. In the form shown in Figs. 9 to 12, the knife-sections *j'* are modified in a manner to be hereinafter described.

In my prior invention about every foot there is a clip *o* secured on the finger-bar *f* 75 by the bolts *h* passed through the parallel slots in said clips *o*, by which their position toward and from the fingers may be adjusted. In my present invention, the same general form of clips *o* are provided, the only 80 difference being that said clips *o* are wider, or rather extend farther forward in order to coöperate with the lugs *n*, which are also placed farther forward in order to secure a more efficient coöperation of the inclined 85 bearing surface formed on the top of the lug with the coöperating similarly inclined bearing surface formed on the under side of the forward edge of the clips to hold the sickle-bar down with the knife-sections *j* in engagement with the ledger-plates *l* no matter how 90 difficult the cutting may be.

In my prior invention the lugs *n* were rigidly secured in place on the knife-sections by being formed integral with the clip-blocks 95 *m*, which are shown as riveted on the knife-sections by the rivets *k*. In the preferred form of my present invention, I provide said clip-block *m* with ears *m'* projecting upward from the rear edge thereof, and I provide 100 the lug *n* with a hinge extension *n'*, so that a pivot pin *n''* serves to hold the lug *n* always connected to the block *m* whether the sickle be in the normal position shown in Figs. 1 and 2, with the bottom of the lug *n* resting 105 on the knife-section *j* in the recess *m''* formed in the block *m* or not, said recess having vertical edges and having a shape correspond-

ing to the shape of the bottom of the lug n in cross section, so that the lug is held from any material movement in the block m , and that without any straining on the hinge mechanism described, which is provided merely to keep the lugs attached to the cutter-bar and prevent their being lost while the sickles are removed for grinding. The position assumed by the lugs during the 10 grinding operation will be readily perceived from Fig. 3, where the dotted circle indicates the stone upon which the knife-sections are held during the grinding operation.

As I have heretofore stated, the hinge is 15 provided merely to prevent the possibility of the removable lugs n being lost, and where the user is willing to take chances on their being lost, I employ the modification shown in Figs. 6, 7 and 8, where the lug n is constructed exactly like the lug shown in Figs. 20 1 to 5, but the hinge portion n' is omitted, and in that case it will be understood that the ears m' are omitted from the block m .

In Figs. 9, 10 and 11, I have illustrated a 25 possible modification, in which the block m is dispensed with, and the recess m^{20} is formed in the knife-section j' , preferably directly over the cutter-bar e . In this case the lug n^2 is provided on its under surface 30 with a projection n^4 of substantially the thickness of the knife-section j' and having the same shape in horizontal cross-section as the aperture m^{20} , in which it fits when the parts are in operative position, as shown 35 in Fig. 9. In this form the same hinge portion n' is employed, but the ears m^{11} in this case are preferably made integral with the section j' .

In the final modification shown in Fig. 40 12, the knife-section employed is just the same as that shown in Figs. 9 and 10 except that the ears m^{11} are omitted, while the lug n^5 is the same as that shown in Figs. 9 and 11 except that the hinge extension n' is 45 omitted.

In using my invention, it will be understood that when the sickle is in the machine, the lugs are always in place coöperating with the clips; but when the sickle is being 50 ground, the lugs, in the form shown in Figs. 1 to 5 and 9 to 11, drop out of place and hang down out of the way, as shown in Fig. 3.

Where the form shown in Figs. 7, 8 and 55 12 is employed, when the sickle is removed for grinding, as soon as it has been drawn out so that the lugs are clear of the clips o , the lugs are picked out of their recesses in the sickle and preferably put in the user's 60 pocket until the grinding is completed. When the sickle is ground and put back in place, it is shoved in until the sections having the recesses n^2 are next to the clips, but not beneath them, when the lugs are put 65 back in place and the sickle shoved home

and connected up to the pitman in the customary manner. During the operation of the machine, the lugs are never entirely out from under the clips which hold them in place, and the combined action of the lugs and clips serves to hold the knife-sections down on the ledger-plates to insure a shear cut, as it will be obvious that the harder the grass presses the sickle back, the more certainly the knife-sections will be forced by 75 the cam action of the coöperating inclined surfaces down upon the ledger plates.

While I have shown and described my invention as embodied in the form which I at present consider best adapted to carry out its purposes, it will be understood that it is capable of some modifications, and that I do not desire to be limited in the interpretation of the following claims except as may be necessitated by the state of the prior art. 85

What I claim as new, and desire to secure by Letters Patent of the United States, is:

1. In a device of the class described, the combination with a finger-bar, and guard-fingers carried thereby, of a cutter-bar and knife-sections secured thereto adapted to reciprocate on the finger-bar, a plurality of lugs having bearing surfaces inclined relatively to the plane of the knife-sections and hinged thereon, and retaining clips carried by the finger-bar and having correspondingly inclined bearing surfaces coöperating with the first-mentioned bearing surfaces. 90

2. In a device of the class described, the combination with a finger-bar, and guard-fingers carried thereby, of a cutter-bar and knife-sections secured thereto adapted to reciprocate on the finger-bar, a plurality of lugs having bearing surfaces inclined relatively to the plane of the knife-sections and 100 hinged thereon, retaining clips carried by the finger-bar and having correspondingly inclined bearing surfaces coöperating with the first-mentioned bearing surfaces, and means independent of the hinges for holding the lugs in operating position. 105

3. In a device of the class described, the combination with a finger-bar, and guard-fingers carried thereby, of a cutter-bar and knife-sections secured thereto adapted to reciprocate on the finger-bar, a plurality of lugs having bearing surfaces inclined relatively to the plane of the knife-sections and hinged thereon, retaining clips carried by the finger-bar and having correspondingly inclined bearing surfaces coöperating with the first-mentioned bearing surfaces, and means independent of the hinges for holding the lugs in operating position, said means consisting of a recess carried by the knife-sections and a correspondingly shaped portion of the bottom of the lug which enters said recess, for the purpose described. 115

4. In a device of the class described, the combination with a finger-bar, and guard- 120

5 fingers carried thereby, of a cutter-bar and knife-sections secured thereto adapted to reciprocate on the finger-bar, a plurality of lugs having bearing surfaces inclined relatively to the plane of the knife-sections, and retaining clips carried by the finger-bar and having correspondingly inclined bearing surfaces coöperating with the first-mentioned bearing surfaces, said knife-sections
10 having a plurality of recesses associated therewith, in which recesses the lugs are

held by the overhanging retaining clips while the machine is in operation and from which they can be removed while the knife-sections are being ground.

15 In witness whereof, I have hereunto set my hand and affixed my seal, this 28th day of October, A. D. 1913.
